UNITED STATES PATENT OFFICE.

GEORGE H. GILMAN, OF BELMONT, MASSACHUSETTS.

DRILLING MACHINE.

Application filed January 6, 1923. Serial No. 611,172.

My invention relates to fluid pressure motors and particularly though not exclusively to rock drills.

My invention will be best understood from the accompanying drawing and following description of one specific embodiment of my invention selected for illustrative purposes, while the scope of my invention will be more particularly pointed out in the appended claims.

In the drawings:—

Fig. 1 is a longitudinal section of a hammer rock drill;

Fig. 2 is a longitudinal section on the line 15 2—2 of Fig. 1;

Fig. 3 is a section on the line 3—3 of Fig. 2;

Fig. 4 is a section on the line 4—4 of Fig. 3; and

Fig. 5 is a section on the line 5—5 of Fig. 2.

Referring to the drawings I have illustrated a drill steel 1, the shank 3 of which is received in the chuck 5 in such manner 25 that the drill steel is constrained to rotate with the chuck. Rearwardly of the drill steel I provide a hammer piston, the latter as shown having the head 7 and the rearward and forward extensions 9 and 11, these 30 extensions, as clearly illustrated by Figs. 1 and 2 of the drawings, being of smaller diameter than the head, and the extension 9 being reduced in diameter at 13 adjacent its juncture with said head.

As illustrated the section 15 of the casing for the machine is provided with a bore 17 in which the head 7 of the piston reciprocates and with the bore 19 in which the forward extension 11 reciprocates. To the 40 rearward end of the casing section 15 is fitted the section 21 to which is rigidly and permanently secured the casing section 25 received in the bore 23 of the section 21. Axially of the section 25 is a bore 27 in 45 which reciprocates the rearward extension 9 of the piston. Interiorly of the section 21 section 25 is provided with the exterior grooves 29, 31 and 33. As best shown by Figs. 1 and 2, the section 25 at the rearward 50 side of the section 21 is provided with a flange 35 which abuts the rearward side of section 21, while rearwardly of the flange the section 25 is reduced in diameter at 37, the extreme rearward end of the section 25 being reduced to a still smaller diameter portion 39 to provide the shoulder 41.

For conducting motor fluid to the machine the section 21 herein is provided with a motive fluid connection 43 from which leads a passage 45 to the annular groove 33, said 60 passage being controlled by the throttle valve 47. Leading from the groove 33 are the diametrically oppositely positioned radial passages 49 which intersect the bore 27. Leading from the passages 49 rearwardly 65 through the wall in the section 25 are passages 51 which open into the bore 27 at its extreme rearward end, this latter being effected by means of an annular enlargement 53 of the bore 27 which intersects said 70 passages 51. Further the passages 49 and 51 are caused to open into the bore 27 by means of slots 55 formed in the interior of the wall of the bore 27 and intersecting these 75 passages. Leading from the bore 27 in the plane of the slots 55 are the diametrically oppositely positioned radial passages 57 which connect with the annular groove 31. Leading from the groove 31 are passages 59 which enter the forward end of the bore 17 80 by means of ports 61.

Herein for controlling the exhaust, midway the length of the bore 17 is an arcuate slot 63 with which connects a rearwardly extending passage 65 which communicates 85 with the exhaust nozzle 67 of the machine.

The operation of the parts so far described is as follows: When the valve 47 is turned to cause motive fluid to enter the groove 33 the motive fluid passes by the way of the passages 49 and 51 and groove 53 to the interior of the bore 27. This occurs continuously while the machine is in operation; consequently a continuous pressure is maintained on the rearward end of the rearward 90 piston extension 9. When the parts are in the position shown by Figs. 1 and 2 motive fluid passes from the bore 27 through the passages 57 to the groove 31, whence it is conducted by means of the passages 59 to the forward end of the bore 17, the grooves 55 at this time being uncovered by the piston extension to augment the supply of air to the bore 17. The admission to the forward 95 end of the bore 17 drives the piston rearwardly, motive fluid heretofore admitted to the rearward end of the bore 17 having in the position of parts under consideration escaped to the atmosphere through the groove 63, passage 65, and exhaust nozzle 100 110 67. When the piston moves rearwardly the extension 9 closes the slots 55 and passages

57, and when the piston reaches the rearward portion of its stroke the reduced portion 13 of the extension 9 establishes communication between the passages 49 and the 5 rearward end of the bore 17. Consequently the piston travels forwardly under the influence of the air on the rearward faces of the head 7 and extension 9, the motive fluid being permitted to escape from the forward 10 end of the bore 17 by way of the groove 63.

As the specific way in which the piston is caused to reciprocate forms no part of my present invention it is believed unnecessary to further describe the same.

15 Referring to Fig. 1, it will be noticed that as illustrated the reduced diameter portion 39 of the casing section 25 has mounted thereon the sleeve like section 69 provided at its forward end with the flange 71 abutting the shoulder 41 of the section 25. Surrounding the section 69 is the section 73 which is rigidly and permanently secured to the section 69. In the interior surface of the section 69 and the interior surface of the 25 section 73 are formed registering annular grooves 75 and 77 respectively, which together form a motive fluid reservoir for a purpose hereinafter described. The sections 69 and 73 are held in assembled relation with 30 the machine by means of the flanged plug 78 which is screw-threaded into the socket 80 formed in the rearward end of the section 25.

The reduced diameter portion 37 of the section 25 forms a bearing for a gear wheel 35, opposite sides of which fit the flanges 71 and 35 in a fluid tight manner.

Intermediate its ends the exterior of the bearing afforded by the reduced portion 37 of the casing is shown as cut away at 40 to form crescent shaped chambers 83 best shown by Figs. 3 and 4. The gear wheel 79 is provided with cylindrical bores 85 which intersect the interior surface of the wheel and are enlarged at one side thereof as is shown at 87 in Fig. 3. In these bores are mounted the oscillatory plugs 89 the exteriors of which are formed to fit the bores 85 and their enlargements 87, while the cut away portions 91 of the plugs are constructed to fit the exterior surface of the adjacent portion of the section 25. In this manner the portion of the plug which fits the enlargement 87 of the bore 85 forms a wing 92. From the enlargement 87 behind the 55 wing are drill holes 93 which open on the exterior of the gear wheel. At opposite ends the gear 79 is recessed to receive the plates 94 which close the ends of the bores 85 and abut the ends of the plugs 89, the plates being held in position by means of pins 95 as shown in Fig. 4.

Herein for conducting motive fluid to the chambers 83 is a pair of passages 97 each of which, as best shown by Figs. 3 and 4, 60 leads from the groove 75 through the mem-

ber 69 and section 25 and opens into one of the respective chambers 83 near the end of the chamber as shown at 97 in Fig. 3. Communicating with the other ends of the chambers 83 are passages 99 which open into the groove 29, these passages serving to exhaust the motive fluid from the chambers. As shown by Fig. 2 the groove 75 is placed into communication with a source of motive fluid supply by way of a passage 101 which is formed through the section 73, the section of the casing 103 enclosing the gear and the section 21, and is controlled by the valve 105. The groove 29 is placed in communication with the exhaust nozzle 67 of the 80 machine by way of a passage 107 formed through the section 21, and for venting leakage the interior of the section 103 is placed in communication with the passage 109 by way of the passage 85.

From the foregoing it will be seen that when the valve 105 is open motive fluid will flow into the chambers 83, and acting upon the plugs 89 will cause the gear 79 to rotate, the plugs being caused to bear against the 90 section 25 because of the unbalanced pressure of the motive fluid upon the wings 92 of the plugs. The motive fluid admitted through the passages 97 exhausts through the passages 99 when the plugs uncover the 95 latter, the parts being so arranged that before one plug uncovers the passage 99 the plug behind it overruns the corresponding passage 97.

It will be understood that the gear 79 and 100 plugs 89 together form the rotor of an expansible chamber fluid pressure motor of the rotating cylinder type; further, that in common with all motors of this type the rotor has a working pressure surface and the 105 stator a pressure abutment surface, the motive fluid acting between the working pressure surface and pressure abutment surface to cause movement of the rotor.

To cause the motor described to rotate 110 the chuck I provide at opposite sides of the machine gears 111 which mesh with the gear 79 and are keyed to shafts 113 extending through the casing at opposite sides thereof. The shafts are mounted in bearings 115 and carry at their forward ends eccentrics 117 integrally formed with the shafts. Mounted upon opposite eccentrics 117 are yokes 119, each of which is provided with the internal gear teeth 121 in mesh 120 with external gear teeth 123 on the chuck 5. When the shafts rotate the eccentrics give the yokes a gyratory motion which causes the chuck to slowly rotate. It will be understood by this construction that the 125 motor is connected to the chuck by means of reduction gearing.

Although I have described for purposes of illustration one specific embodiment of my invention it is to be understood that 130

within the scope of my invention wide deviations may be made therefrom without departing from the spirit of my invention.

Claims:

5. 1. In a hammer rock drill, a chuck formed for carrying a drill steel, a hammer piston having a head and a rearward extension of smaller diameter, a casing having bores in relatively non-rotatable parts for receiving said head and extension of said hammer piston and said chuck, means for admitting motive fluid to said bores for acting upon said piston, a member surrounding the portion of said casing receiving said extension of said hammer piston, means for causing rotation of said member by admitting and exhausting motive fluid between said member and the portion of said casing which said member surrounds, and reduction gearing for transmitting the rotation of said member to said chuck for rotating the latter.
10. 2. In a hammer rock drill, a chuck formed for carrying a drill steel, a hammer piston having a head and a rearward extension of smaller diameter, a casing having bores in relatively non-rotatable parts for receiving said head and extension of said hammer piston and said chuck, means for admitting motive fluid to said bores for acting upon said piston, an expansible chamber fluid pressure motor for rotating said chuck, said motor comprising a rotor surrounding the portion of said casing receiving said extension of said hammer piston, said rotor having a working pressure surface which forms part of the wall of the expansible chamber of said motor, means providing a stationary pressure abutment surface for the motive fluid acting on said working pressure surface, and reduction gearing means connecting said rotor to said chuck for causing rotation of the former to be imparted to the latter.
15. 3. In a hammer rock drill, a chuck formed for carrying a drill steel, a hammer piston having a head and a rearward extension of smaller diameter, a casing having bores in relatively non-rotatable parts for receiving said head and extension of said hammer piston and said chuck, a fluid pressure motor for rotating said chuck, said fluid pressure motor providing an expansible chamber having a rotary working pressure surface and a non-rotary pressure abutment surface, said rotary working pressure surface being formed on a rotor and comprising part of the walls of said expansible chamber, said rotor surrounding the portion of the casing receiving said rearward extension of said hammer piston, means for admitting and exhausting motive fluid to and from said expansible chamber, and reduction gearing means operatively connecting said rotor to said drill steel.
20. 4. In a hammer rock drill, a hammer piston having a head and an extension of smaller diameter, a fluid pressure rotary cylinder expansible chamber motor surrounding said extension of said hammer piston, the rotary cylinder of said motor carrying an annular series of external gear teeth, a chuck formed for carrying a drill steel and reduction gearing operatively connecting said annular series of gear teeth to said chuck for causing the rotation of said cylinder to be imparted to said drill steel.
25. 5. In a rock drill, a hammer piston, a drill steel chuck, a casing having relatively non-rotatable parts for said hammer piston and chuck, an annular member surrounding and being mounted for rotation on said casing, external gear teeth carried by said annular member, said gear teeth being operatively connected to said chuck, and means for causing rotation of said annular member by admitting motive fluid between said member and the portion of the casing which it surrounds.
30. 6. In a rock drill, a hammer piston, a drill steel chuck, a casing having relatively non-rotatable parts for said hammer piston and chuck, an annular member mounted for rotation on said casing coaxially with said chuck and surrounding said hammer piston, external gear teeth carried by said annular member, said gear teeth being operatively connected to said chuck, and means for causing rotation of said annular member by admitting motive fluid between said member and the portion of the casing which it surrounds.
35. 7. In a rock drill, a hammer piston, a chuck, a casing for said hammer piston and chuck, an external gear member surrounding said casing and piston and having a bearing at said casing, said bearing being formed between its ends to provide at its exterior a chamber closed by said member, means for admitting motive fluid to and exhausting it from said chamber, and motion transmitting means including the gear teeth of said external gear member for connecting said member with said chuck.
40. 8. In a rock drill, a hammer piston, a chuck, a casing for said hammer piston and chuck, a member mounted axially of and having a bearing on said casing, said bearing being formed between its ends to provide at its exterior a chamber closed by said member, means for admitting motive fluid to and exhausting it from said chamber, and motion transmitting means connecting said member with said chuck.
45. 9. In a rock drill, a hammer piston, a chuck, a casing for said hammer piston and chuck, an external gear wheel having a bearing on said casing, said bearing being formed between its ends to provide at its exterior a chamber closed by said gear wheel, means for admitting motive fluid to and

- exhausting it from said chamber, and motion transmitting means connecting said member with said chuck including a gear meshing with said external gear.
- 5 10. In a hammer rock drill, a chuck formed for carrying a drill steel, a hammer piston for operating said drill steel, a rotor for rotating said chuck, a casing for said piston, chuck and rotor, said rotor being journaled on a portion of said casing, and said parts being all mounted in said casing coaxially with each other, means including said rotor and casing formed to provide the fluid chamber of an expansible chamber fluid pressure 70 motor having a working pressure surface and a pressure abutment surface, said working pressure surface rotating with said rotor and said pressure abutment surface being non-rotatable.
- 10 15 20 25 30 35 40 45 50 55 60 65 70 75 80 85 90 95 100 105 110 115 120 125 130
11. In a hammer rock drill, a chuck formed for carrying a drill steel, a hammer piston for operating said drill steel, a gear coaxially arranged with the parts mentioned, a gear meshing with the first mentioned gear and operatively connected with said chuck, a casing for said piston, chuck and gears, and means for admitting motive fluid to said casing to act only on the first mentioned of said gears for rotating both gears.
12. In a rock drill, a chuck formed for carrying a drill steel, a hammer piston for operating said drill steel, a gear coaxially arranged with said chuck and piston, a pair of gears arranged at opposite sides of said first mentioned gear and meshing therewith, said pair of gears being connected to said chuck, and means for rotating all said gears by motive fluid acting only on said first mentioned gear.
13. In a rock drill, a cylinder, having a detachable rear end section, a piston having a head in said cylinder and a reduced extension in said rear end section, a rotary cylinder motor surrounding said rear end section and the cylinder bore for said extension, and a chuck operatively connected to said motor.
14. In a rock drill, a cylinder having a detachable rear end section, a piston having a head in said cylinder and a reduced extension in said rear end section, a motor comprising a rotor and means providing a non-rotary abutment surface, said rotor being mounted in said rear end section concentrically with the bore for said piston, and a chuck operatively connected to said rotor.
15. In a hammer rock drill, a chuck formed for carrying a drill steel, a hammer piston having a head and an extension of smaller diameter, a casing having bores in relatively non-rotatable parts for receiving said head and extension of said hammer piston and said chuck, a member surrounding the portion of said casing receiving said extension of said hammer piston, means for causing 70 rotation of said member by admitting and exhausting motive fluid between said member and the portion of said casing which said member surrounds, and reduction gearing for transmitting the rotation of said member to said chuck for rotating the latter.
16. In a hammer rock drill, a chuck formed for carrying a drill steel, a hammer piston having a head and an extension of smaller diameter, a casing having bores in relatively non-rotatable parts for receiving said head and extension of said hammer piston and said chuck, an expansible chamber fluid pressure motor for rotating said chuck, said motor comprising a rotor surrounding the portion of said casing receiving said extension of said hammer piston, said rotor having a working pressure surface which forms part of the wall of the expansible chamber of said motor, means providing a stationary pressure abutment surface for the motive fluid acting on said working pressure surface, and reduction gearing means connecting said rotor to said chuck for causing rotation of the former to be imparted to the latter.
17. In a hammer rock drill, a chuck formed for carrying a drill steel, a hammer piston having a head and an extension of smaller diameter, a casing having bores in relatively non-rotatable parts for receiving said head and extension of said hammer piston and said chuck, a fluid pressure motor for rotating said chuck, said fluid pressure motor being constructed to provide an expansible chamber having a rotary working pressure surface and a non-rotary pressure abutment surface, said rotary working pressure surface being formed on a rotor comprising part of the walls of said expansible chamber, said rotor surrounding the portion of the casing receiving said extension of said hammer piston, means for admitting and exhausting motive fluid to and from said expansible chamber, and reduction gearing means operatively connecting said rotor to said drill steel.
18. In a rock drill, a chuck, a piston, a casing for said chuck and piston, a pair of shafts disposed at opposite sides of said casing, an eccentric on each shaft at the side of said chuck, a yoke carried by said eccentricities, said yoke surrounding said chuck and having internal gear teeth meshed with external gear teeth on said chuck, a gear carried by the rearward portion of each shaft, a gear meshing with both of said gears on said shafts, and means for causing said gears to rotate by fluid pressure applied only to said last mentioned gear.
19. In a rock drill, a chuck, a piston, a casing for said chuck and piston, a pair of shafts disposed at opposite sides of said casing, an eccentric on each shaft at the side of said chuck, a yoke carried by said eccentricities.

trics, said yoke surrounding said chuck and having internal gear teeth meshed with external gear teeth on said chuck, a gear carried by the rearward portion of each shaft, 5 a gear having an annular body meshing with both of said gears on said shafts, and means for admitting motive fluid to the space surrounded by said annular body for rotating it.

10 20. In a rock drill, a chuck formed for carrying a drill steel, a hammer piston, a casing for said chuck and piston, and a rotary cylinder motor surrounding said casing and piston, and reduction gearing connecting said cylinder to said chuck.

21. In a rock drill, a chuck formed for carrying a drill steel, a hammer piston, a casing for said chuck and piston, and a motor having a rotary annular cylinder 20 surrounding said casing and piston, and reduction gearing connecting said cylinder to said chuck.

22. In a rock drill, a chuck formed for carrying a drill steel, a piston, a casing for 25 said chuck and piston, an annular member mounted for rotation on said casing and surrounding said piston, movable vanes carried by said annular member and cooperating with said casing, and speed reducing 30 means connecting said annular member to said chuck.

23. In a drilling machine, a chuck, a casing, shafts at the sides of said casing, eccen-

trics carried by said shafts, a yoke carried by said shafts having internal gear teeth meshing with external gear teeth on said chuck, pinions carried by said shafts, a gear meshing with both pinions, a bearing on said casing for said gear, and means permitting motive fluid to act between said gear and casing for causing said gear to rotate.

24. In a drilling machine, a chuck, a casing, shafts at the sides of said casing, eccentrics carried by said shafts, a yoke carried by said eccentrics and having internal gear teeth meshing with external gear teeth on said chuck, three spur gears in mesh, means including but one of said spur gears forming an expansible chamber motor, one of said spur gears being mounted coaxially with said chuck and the others respectively being non-rotatably secured to said shafts.

25. In a motor and reduction gear, a driven member having external gear teeth, a yoke having internal gear teeth meshing with the external gear teeth of said chuck, eccentrics supporting said yoke, shafts carrying said eccentrics, pinions on said shafts, a spur gear meshing with said pinions, a bearing for said spur gear, and means for admitting motive fluid between said spur gear and its bearing for rotating said gear.

In testimony whereof, I have signed my name to this specification.

GEORGE H. GILMAN.

CERTIFICATE OF CORRECTION.

Patent No. 1,616,487.

Granted February 8, 1927, to

GEORGE H. GILMAN.

It is hereby certified that error appears in the printed specification of the above numbered patent requiring correction as follows: Page 3, line 106, claim 7, for the word "at" read "on"; and that the said Letters Patent should be read with this correction therein that the same may conform to the record of the case in the Patent Office.

Signed and sealed this 29th day of March, A. D. 1927.

Seal.

M. J. Moore,
Acting Commissioner of Patents.
